VEHICLE FRAME

Roy M. Desbrow, Azusa, Calif., assignor to Go Kart Manufacturing Company, Inc., Azusa, Calif., a corporation of California

Filed Apr. 22, 1960, Ser. No. 60,286

Term of patent 14 years

(Cl. D14—3)

Fig. 1

Fig. 2

Fig. 3

Fig. 1 is a top plan view of a vehicle frame showing my new design;

Fig. 2 is a side elevation; and

Fig. 3 is a front end view.

The portions of a vehicle shown in broken lines are included for illustrative purposes only.

I claim:

The ornamental design for a vehicle frame, as shown and described.
